TOY

Filed July 30, 1931

UNITED STATES PATENT OFFICE

ELMER L. HEWITT, OF CHURCHVILLE, NEW YORK, ASSIGNOR TO ALL FAIR INCORPORATED, OF CHURCHVILLE, NEW YORK, A CORPORATION OF NEW YORK

TOY

Application filed July 30, 1931. Serial No. 554,113.

The invention relates to toys of the type adapted to be propelled, usually by being drawn over a surface, and which simulate the movements and sound of a living animal or bird.

The invention provides a toy of the character aforesaid embodying a movable head, independently movable jaws, and a sound producing mechanism, all actuated by movement derived from a mechanism set in motion as the toy is propelled or drawn over a surface.

One of the chief features of the invention is the provision of a toy which will withstand hard usage without liability of derangement or crippling of the parts, and which embodies a small number of elements readily accessible for any desired purpose.

For a full understanding of the invention and the merits thereof, reference is to be had to the drawing hereto attached and the subjoined description in which corresponding parts are designated in the several views of the drawing and referred to in the specification by like reference characters.

In the drawing:—

Figure 1 is a vertical, central, longitudinal section of a toy illustrative of an embodiment of the invention, the head being lowered and the dotted lines showing the head raised.

Fig. 2 is a transverse section on the line 2—2 of Fig. 1.

The numeral 1 designates the body of the toy which is representative in the present instance, of a duck, and which is hollow to receive the operating parts. The toy is mounted upon wheels 2 and 3, the latter being secured to a crank shaft 4. The head 5 is connected to the body 1 by means of links 6 and 7. By providing two links 6 and 7, the head 5 is maintained approximately parallel to a predetermined position throughout its various movements. A fixed

jaw 8 projects from the head 5 and a movable jaw 9 is pivoted to the head and preferably opens by gravitational action. The head 5, like the body 1, is hollow to receive the pivotal ends of the jaw 9 and links 6 and 7.

Under normal conditions the head 5 oc-

cupies a lowered position, as indicated by the full lines in Fig. 1, and is adapted to be extended or raised, as shown by the dotted lines. The links 6 and 7 constitute in effect the neck. A link 10 connects the lower end of the link 6 with the crank portion of the crank shaft 4, and in consequence, said link receives a vibratory movement as the object is drawn over a surface. The movement of the link 6 effects an alternate raising and lowering of the head 5. When the head 5 is elevated, the pivotal jaw 9 is lowered and when the head 5 is lowered, the jaw 9 is closed. A stop or projecting portion 11 engages a portion of the jaw 9 adjacent its pivot and limits the opening of the jaw. A projecting portion 12 adjacent the pivot of the jaw 9 coacts with a portion of the link 6 and effects a closing of said jaw, as indicated most clearly in Fig. 1 of the drawing.

A sound producing mechanism is associated with the toy and is disposed within the same and is designed to emit a sound corresponding to the voice of the object of which the toy is representative.

In the present instance, the construction is such as to emit a quacking sound simulating the voice of a duck. The sound producing mechanism comprises a pair of cylinders 13, a diaphragm 14 stretched thereover, and a vibrant element 15, the latter consisting of a spring secured at one end to the body 1 and having its opposite end free to be actuated by means of the link 10. The intermediate portion of the spring 15 coacts with the diaphragm 14 to produce the desired sound when the toy is in motion. The vibrant element 15 is adapted to be actuated in any manner by means of the link 10 and, as shown, a notch 16 is formed in the link and provides a stop which coacts with the free end of the spring 15.

A string 17 or analogous element is attached to the body of the toy and provides convenient means for drawing the same over a surface. As the toy is propelled the supporting wheels 2 and 3 are rotated, and by reason of the crank connection of the link 10 with the shaft 4 of the wheels 3, said link is

reciprocated and imparts a vibratory movement to the link 6 whereby the head 5 is raised and lowered. At the same time, the element 15 is vibrated and coacting with the diaphragm 14, produces a quacking sound simulative of that of a duck of which the present toy is a representation. As the link 6 vibrates, the head 5 is raised and lowered and is maintained parallel to a given position throughout its movements by reason of the link 7. As the head 5 raises, the jaw 9 lowers, and when the head 5 lowers, the jaw 9 closes.

It is to be understood that the invention may be readily adapted to any object representative of an animal or bird. It is further observed that the device embodies a small number of parts which are readily accessible at all times.

In practice, the head and body may consist of side pieces of sheet material between which elements are secured. The link 6 constituting the neck proper may be formed with a kerf to receive the link 7 and forward portion of the link 10. The portion partly cut from the link 10 to form the notch 16 is adapted to be bent laterally to provide a projection 18 which extends across the path of the vibrant element 15 for actuating the same when the toy is in motion.

What is claimed is:

1. In a toy of the character specified, a body, a movable head, a link pivotally connecting the head to the body, a second link forming pivotal connecting means between the head and body to maintain the head approximately parallel to a predetermined position during its various movements, means actuated by propulsion of the toy to impart a vibratory movement to one of the aforementioned links to effect a raising and a lowering of the head, a fixed jaw projecting from the head, a movable jaw pivoted to said head and adapted to be simultaneously actuated as the head is raised and lowered, a stop to limit the opening of the movable jaw, and stop means between the movable jaw and one of the links to effect a closing of the movable jaw and the holding of the same in closed position.

2. In a toy of the character specified, a body, a head movable relative to the body, said head being provided with jaws, one of which is pivotally mounted on the head and is movable relative to the other jaw, links pivotally connecting the head with the body, the movable pivoted jaw being adapted to be actuated by one of said links so as to move relative to the other jaw at a time when the head is moved relative to the body, stop means for limiting the opening movement of the movable jaw, and actuating means for effecting a raising and a lowering of the head and operated by propulsive movement of the toy.

3. A toy of the character specified, comprising a body, supporting wheels therefor,

a crank shaft forming connecting means between a pair of supporting wheels, a movable head provided with a fixed jaw, a movable jaw pivoted to the head, links pivotally connecting the head with the body and adapted to maintain the head in given aspect, a sound producing mechanism, and a link connecting the crank shaft with one of the aforementioned links and adapted to actuate the sound producing mechanism.

4. A toy of the character specified, comprising a body, pairs of front and rear wheels, a crank shaft connecting the rear wheels, a movable head provided with a fixed jaw, a movable jaw pivoted to the head, links pivotally connecting the head with the body, a link connecting the crank shaft with one of the aforementioned links, and a sound producing mechanism adapted to be actuated by the link connected to the crank shaft.

5. A toy of the character specified, comprising a body, a hollow head, a fixed jaw projecting from the head, a movable jaw pivoted within the head, a pair of links pivoted at one end within the hollow of the head to the rear of the movable jaw, and pivoted at the opposite end to the body, one of the links being engageable with the movable jaw to effect a closing thereof and maintain it in closed position, stop means within the head to limit the opening of the movable jaw, and actuating means operated by propulsive movement of the toy to effect a raising and lowering of the head and a simultaneous opening and closing of the jaws.

6. A toy of the character specified comprising a body, a head member pivotally connected with the body by means comprising a movable link, which head member is provided with jaws movable in respect to each other, at least one of which is movably mounted on and carried by the head member, the jaw last referred to being operatively associated with said link whereby during at least a part of the movement of the link the jaw is thereby caused to move relative to the other jaw and at a time when the head member is being moved relative to the body.

7. A toy of the character specified comprising a body, a head member movable relative to the body, actuating means operative by the propulsive movement of the toy for effecting the relative movement between the body and the head member, said head member having jaws at least one of which is movable relative to the head member, said toy having a link pivotally connected to the head member and to the body and which link is associated with the movable jaw so that a portion of the link which is distant from the place where it is connected to the head member functions during at least a part of the movement of the link to effect a movement of the jaw relative to the head member when the

head member is being moved relative to the body.

8. A toy of the character specified comprising a body, a head member pivotally connected with the body by means comprising a movable link one portion of which link is pivotally connected to the head member and another portion of which is pivotally connected to the body, said head member having a jaw movably mounted thereupon, and in respect thereto, said jaw having operative engagement with said link whereby during at least a part of the movement of the head member relative to the body said link during the movement thereof causes a movement of the jaw relative to the head member.

9. In a toy of the character specified, the combination of a body member, a head member movable relative to the body member, said head member having a part mounted thereon so that said part can move relative to the rest of the head member, a sound-producing mechanism carried by one of said members, and actuating means operated by propulsive movement of the toy, which actuating means comprises movable elements associated with the body member and the head member to effect relative movement between said members, said actuating means also being associated with said sound-producing mechanism and said part movably mounted on the rest of the head whereby at a time when said part is moved relative to the rest of the head the sound-producing mechanism functions to make a noise.

10. A sound-producing toy of the character specified comprising the combination with the sound-producing mechanism, of a body member, a head member movable relative to the body member, said head member having jaws one of which is movable relative to the other, and actuating means operated by the propulsive movement of the body, which actuating means is operatively associated with said body member and said head member, said movable jaw and said sound-producing mechanism so that by movement of the toy along a supporting surface the actuating means can function to cause the head to move relative to the body member, to cause one of the jaws to move relative to the other jaw and so as to operate said sound-producing mechanism.

5 In testimony whereof, I have hereunto set my hand, this 24th day of June, 1931.

ELMER L. HEWITT.
